COOLING SYSTEM

John C. Raisley, New Haven, Conn., assignor to
Cool-Rite Products Corporation, New Haven,
Conn., a corporation of Delaware

Application January 8, 1934, Serial No. 705,712

4 Claims. (Cl. 62--103)

The present invention has relation to cooling or refrigerating systems of a common type employing apparatus comprising a compressor or pump which is under control of suitable means, such for example as an expansion valve, for forcing circulation of the refrigerant contained in a coil located within the cooling chamber through which circulation of air is induced by means of a motor driven fan.

10 A cooling system as above generally referred to is employed with a refrigerator used for the preservation of food products or in other instances when it is desirable to maintain a given degree of humidity in the air and the main object 15 of this invention is to provide improved means whereby the required relative degree of humidity can be maintained at different temperatures of the air.

In practically all systems where a cooling coil 20 is employed the surface of radiation thereof is increased by fins in the form of plates threaded on the coil.

According to the present invention the fins are employed to also regulate or give the correct 25 degree of relative humidity when the system is in use for the preservation or cooling of food products.

It is understood that in the refrigeration of food, at different temperatures, more or less moisture in the food is caused to evaporate thereby 30 the food may become undesirably dried because the moisture so evaporated passes away. With the improved means now introduced the moisture is condensed, collected and retained on said fins 35 in the form of drops or particles on substantially the entire surface of both sides of the fins thereby holding the condensed moisture in suspended position and materially increasing the area of evaporation.

40 An embodiment of the invention as applied to a cooling or refrigerating system is more fully described hereinafter with reference to the accompanying drawing wherein—

45 Figure 1 is a side elevation showing the arrangement of the apparatus of a cooling system for which the invention is applicable;

Figure 2 is a front elevation of the same apparatus;

50 Figure 3 is a sectional view taken on line 3—3 of Figure 4 looking in the direction of the indicating arrow;

Figure 4 is a side elevation of a fin or moisture collecting and distributing plate with the 55 tube supporting the fin shown in section, and

Figure 5 is an enlarged or exaggerated vertical section of the fin.

In the embodiment shown in the drawing referred to the invention is applied to a cooling system of a common type which requires a cooling chamber such as 1 enclosing the coil 2 therein and a drain 3 is usually provided to carry off excess moisture. A fan 4 driven by a motor 5 is employed to induce circulation of air through the cooling chamber.

The refrigerant is given a forced circulation through the coil 2 and conductor 6 by means of the compressor or pump 7 which is under control of the thermostatic expansion valve 8 in the usual way.

The fins or plates 9 are threaded on the tubes of the coil 2 spaced apart and as said fins are composed of comparatively thin sheet metal a bearing for the fins is provided by drawing out the stock around the central hole to provide the boss 10 and which boss also may operate as the spacing means for the fins. The fins are formed with a series of indentations preferably square and located on both sides of the fins. The purpose of the indentations is to provide pockets or reservoirs on the surfaces of the fins to collect and retain the drops or particles of condensed moisture separated during the defrosting cycle of the coil 2 so that the current of air from the fan will blow the moisture back into the air in a finely atomized state. The edge of the indentations has a tendency to hold the condensed moisture and without these indentations the drops would run together and drip off the bottom edge of the fins and pass away through the drain 3. The pockets 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790

The improvement hereinbefore described provides means for determinably maintaining the required relative degree of humidity under proper control regardless of external atmospheric conditions.

It will be understood the fins may be variably spaced apart, with the pockets of any suitable shape and located on one side only, therefore it is to be understood, such modifications or any others coming fairly within the terms of claims hereunto appended shall be covered thereby.

I claim:

1. In a system of cooling or refrigeration, a

refrigerating coil, a plurality of fins or plates having a central perforation with turned-in edges forming a boss threaded on said coil and said fins or plates having a series of indentations on both sides thereof alternately arranged forming pockets adapted for the collection and distribution of moisture.

2. In a system of cooling or refrigeration, a refrigerating coil, a plurality of fins or plates threaded on said coil one above the other and said fins or plates having a series of indentations on both sides, surfaces thereof forming pockets adapted for the collection and distribution of moisture.

3. In a system of cooling or refrigeration, a refrigerating coil, a plurality of fins or plates threaded one above the other on said coil, means comprising a boss on each fin or plate for spacing

said fins or plates apart and said fins or plates having a series of substantially square shaped indentations on both sides thereof forming pockets adapted for the collection and distribution of moisture.

4. In combination with a system of and means for cooling or refrigeration comprising a refrigerant coil and a fan for causing forced flow of air, a plurality of fins or plates threaded on said coil one above the other to form a broken column and spaced apart from an adjacent column by bosses on said fins or plates, said fins or plates having a series of indentations on both sides forming pockets to receive and suspend collected moisture over an extended surface to increase the area of evaporation under action of the current of air from said fan.

JOHN C. RAISLEY.
